(57) **CLAIM**

We claim the ornamental design of a charge holder, as shown and described.

DESCRIPTION

FIG. 1 is an upper, front, left perspective view of a charge holder showing our new design;

FIG. 2 is lower, front, left perspective view of the charge holder of FIG. 1;

FIG. 3 is an upper, front, right perspective view of the charge holder of FIG. 1;

FIG. 4 is lower, front, right perspective view of the charge holder of FIG. 1;

FIG. 5 is an upper, rear, right perspective view of the charge holder of FIG. 1;

FIG. 6 is a lower, rear, right perspective view of the charge holder of FIG. 1;

FIG. 7 is an upper, rear, left perspective view of the charge holder of FIG. 1;

FIG. 8 is a lower, rear, left perspective view of the charge holder of FIG. 1;

FIG. 9 is a front elevated view of the charge holder of FIG. 1;

FIG. 10 is rear elevated view of the charge holder of FIG. 9;

FIG. 11 is a left side elevated view of the charge holder of FIG. 9;

FIG. 12 is a right side elevated view of the charge holder of FIG. 9;

FIG. 13 is a top plan view of the charge holder of FIG. 1; and,

FIG. 14 is a bottom plan view of the charge holder of FIG. 1.

The broken lines consisting of dashes show structure that forms no part of the claimed design. The broken lines consisting of a double-dot/dash pattern show a boundary of the claimed design.
